9 Claims. (Cl. 241—284)

This invention relates to an impact mill and more particularly to an impact mill for attrition reduction in size of rock particles by the impact or collision fracturing of the particles to obtain a smaller substantially rounded product.

The applicant is not aware of any commercial apparatus or method for producing a substantially rounded product of the nature of sand from particles of rock. Several known commercial apparatus and methods deal with impact pulverization in which coarsely ground raw material is circulated at high velocity in an elastic fluid in a chamber having a closed continuous circuit. The moving particles of material collide with each other and as a result of these mutual impacts the material is pulverized. Other forms of pulverizers involve propelling the material with great force against a target.

Such apparatus and methods are not suitable where it is desired not to pulverize the material but to reduce it to substantially rounded particles of predetermined size. It has been found by the applicant that pulverization can be largely avoided and a rounded product obtained by propelling certain of the particles against other of the particles which are stationary with sufficient force to chip protruding corners including fracture of crystal structure of at least some of the moving and stationary particles. By fracturing the crystal structure of rock particles, a round product is obtained and by recycling over-size particles (hereinafter referred to as "overs") most of the rock particles can be reduced substantially to a predetermined rounded size.

In one of its aspects, an impact mill for reducing the size of rock particles in accordance with this invention includes an elongated tube of predetermined length having a receiving end and a discharge end, an attrition bin disposed in co-operative alignment with said tube and communicating with the discharge end thereof, means for introducing rock particles to said tube, means for causing said particles to move through said tube at high velocity, whereby said particles are hurled from said discharge end into the attrition bin, said bin being adapted to accumulate said particles, said co-operative alignment of said bin with said tube serving to direct said particles hurled from the discharge end of said tube into collision with the particles accumulated in said bin to reduce the size of at least some of said particles.

In another of its aspects, an impact mill for reducing the size of rock particles includes at least two elongated tubes of predetermined length and an equal number of attrition bins, each of said tubes having a receiving end and a discharge end; said bins being co-operatively aligned in series with said tubes for the successive reduction of said particles; one of said discharge ends communicating with each of said bins; means for introducing rock particles to a selected first tube, means for impelling said particles through said selected first tube at high velocity into the bin communicating with the discharge end thereof, means for introducing rock particles in said bins to the receiving ends of said tubes, means for impelling said particles through said tubes at high velocity into the bins communicating with the discharge ends thereof, each of said bins being adapted to accumulate at least some of said particles, whereby said particles are impelled

2

through said tubes from bin to bin and said co-operative alignment of said bins with said tubes serves to direct said particles impelled from the discharge ends of said tubes into collision with said accumulated particles in said bins to reduce the size of at least some of said particles.

In drawings which illustrate embodiments of the invention,

FIGURE 1 is a side elevation view of one embodiment,

FIGURE 2 is a diagrammatic plan view partly in section of another embodiment,

FIGURE 3 is a sectional elevation view taken along the lines 3—3 of FIGURE 2,

FIGURE 4 is a sectional elevation view taken along the lines 4—4 of FIGURE 2,

FIGURE 5 is an enlarged, detailed elevation view of the feed arrangement at point "A" in FIGURE 2,

FIGURE 6 is a sectional diagrammatic plan view of another embodiment,

FIGURE 7 is a sectional, diagrammatic elevation view of the embodiment of FIGURE 6, and

FIGURE 8 is a sectional view taken along the lines 8—8 of FIGURE 6.

The impact mill illustrated in FIGURE 1 comprises an elongated tube 10, having a receiving end 11 and a discharge end 12 communicating with an attrition bin 13. A fan 14 connected to the receiving end 11 of the tube 10 is capable of creating winds of from 50 to 200 miles per hour in tube 10 to impel rock particles 15 through the tube and into the bins at high velocity. The rock particles 15 are introduced to the tube by the feed hopper 16 which is detachably connected to the tube 10 adjacent the receiving end 11 thereof. The feed hopper 16 includes a vibrating feeder 16' which introduces the particles 15 to the tube. An aperture 17 in roof 18 of the bin 13 permits the escape of dust from the bin 13 and aperture 19 in the floor 20 of the bin is opened and closed by plate 21 slidably connected to the floor 20. From time to time the particles in the bin are withdrawn through aperture 19 and screened, with "overs" (not shown) being recycled. At the beginning of the reduction operation there will be particles in the bin so that those introduced to the tube 10 through the hopper 16 and impelled through the tube into the bin will collide with the stationary particles in the bin.

The impact mill illustrated in FIGURES 2 to 5 inclusive is a modification of that shown in FIGURE 1, in which four attrition bins 13 and four tubes 10 are co-operatively aligned in series for the successive reduction of rock particles. In the preferred arrangement, the bins will be erected on sloping ground (see FIGURE 4) with the first bin located highest on the slope, so that it will not be necessary to slope the tubes upwardly from bin to bin with consequent loss in momentum of the rock particles.

At the beginning of the reduction run each bin has a covering of particles 15 (not shown) to protect the bin floors 20. Each bin floor 20 can be made of wood and comprises a sloping portion 23 and a substantially horizontal portion 24 adapted to hold a predetermined minimum quantity of rock particles in each bin to protect the floors thereof. The receiving end 11 of a selected first tube 22 communicates with the first bin. Rock particles (not shown) are introduced to the tube 22 by feed hopper 16 detachably connected thereto. The feed hopper 16 includes a vibrating feeder 16' which introduces the particles to the tube 22. Winds in tube 22 created by the fan 14 connected to the receiving end of the tube impel the rock particles in the tube at high velocity into the first bin. The rock particles impelled from the discharge end 12 of the tube 22 collide with the stationary rock particles in the bin. An aperture 25 in the horizontal

portion 24 of each bin floor (see FIGURE 3) communicates with the next tube in the series, the receiving end of which is located beneath the bin floor. The particles over and above the predetermined minimum quantity in each bin necessary, to protect the floor of the bins slides into the aperture 25 and into the next tube when they are impelled at high velocity into the next bin in the series. In this way the rock particles progress from the first selected tube 22 to the first bin and from bin to bin via the tubes until the third or penultimate bin is reached (see FIGURE 3).

At this stage of the reduction series, the particles can be impelled into the fourth bin where they can be stored and from time to time drawn off for storage elsewhere or the particles can be recycled through the product return duct 27 (see FIGURE 4).

The particles to be introduced to the product return duct 27 pass through the air lock 26. An additional fan (not shown) is provided to convey the particles to the mill screen (also not shown). Air lock 26 is a louvered aperture (details not shown) and the louvers are adapted to close in the event of back pressure in the product return duct 27 thereby preventing blow backs in that duct. The duct 27 leads to a mill screen (not shown) where the particles are sized. "Overs" are recycled.

As the rock particles, hurled into the bins from the discharge ends of the tubes, come into collision with the stationary particles in the bins, considerable dust is created. Advantage is taken of the air stream issuing from the discharge ends of the tubes into the attrition bins to remove this dust. A directional baffle 30 is located in each bin being disposed parallel to the bin floor 20 in spaced relationship from the front wall 31 of each bin. As the product laden air stream enters an attrition bin the air flow is as shown by the broken line in FIGURE 3. The air bounded by the baffle 30 and the floor 20 will be in turbulence and the heavier rock particles will either roll down the bin floor 20 or fall out of the air stream as it passes along the underside of the baffle 30. These particles will find their way to the aperture 25 in the bin floor and through which they will pass and then be carried to the next bin by the next tube. The dust will be comparatively lighter than the product and since the air in the bins will be under pressure from the air stream issuing from the discharge ends of the tubes, the dust will be carried by the air stream into the area between the two rows of attrition bins, in which area it will proceed downwardly in a direction from the first bin to the last bin where it is introduced to the atmosphere (not shown) under a lower pressure and allowed to precipitate. A second directional baffle 32 in each bin serves to slow down the dust bearing air stream so that when the stream issues from one of the bins it merges smoothly with the downward flow of dust laden air.

While drawings 2 to 5 inclusive illustrate a series of four bins and four tubes being a modification of the embodiment shown in FIGURE 1, it is not intended to infer that four is the maximum or optimum number of bins. It may be that as many as forty or more bins will prove desirable. The decision will be based upon such variables as the size of the rock particles to be reduced, the contour of the ground on which the bins are to be erected, the degree of roundness of the produce required, the fracture habit of the particular rock used for raw material and the velocity of the collision between the moving and the stationary rock particles. The velocity itself will vary with air-speed, air-turbulence, mill dimensions and dryness of mill feed and air humidity. The fracture habit of the rock is dependent on tectonics of the habitat of the rock, the crystal size and composition and the degree of inter-crystalline and/or intergranular cementation.

The flow disclosed in FIGURES 2 to 5 inclusive is hopper—feeder—reduction bins—in-circuit storage—return fan and duct—screen—hopper, etc. By an alternative arrangement, not shown in the drawings, the feeder

and screen may be placed at the bottom of the incline rather than at the top so that the hopper and feeder only once handle any rock particle. With this system the air-lock 26 may be located between the screen and the return duct so that the flow will be hopper—feeder—screen—return fan and duct—reduction bins—screen—return fan and duct, etc. There would be no in-circuit storage and no in-circuit feeder. The rock particles would repeatedly pass through the screen, air lock, return fan and reduction bins in that order.

An impact mill having a helical tube 33 is illustrated in FIGURES 6 to 8 inclusive. In cross section (see FIGURE 8) the outer wall 34 of the tube 33 is elliptical and the inner wall 35 is circular with the circular passage 36 being radially inwardly off-set from the central axis of the tube so that the greatest thickness of the tube wall is at the outer perimeter of the helix. Crushed rock particles from a crushing plant (not shown) are stored in the mill bin 37 from which the rock particles are conveyed by a belt conveyor 38 to the vibrating screen 39 where the rock particles are separated into three sizes, namely, "fines," "overs," and "product." The "fines" will be stored and run through the tube at a later date for a secondary product. The "overs" will drop down into the air stream of the helical mill created by the fan 40 located in the receiving end of the helical tube and as the particles are blown through the helical tube they tend to roll around the wall of the tube becoming rounded in the process. At the discharge end of the helical tube, the rock particles are impelled into the attrition bin 41 which functions similarly to those previously described and where further reduction in size occurs when the discharged particles collide with stationary particles in the bin. From the attrition bin the rock particles again pass over the screen and are further separated as in the first instance. The "overs" will again be put through the tube and the "fines" will be conveyed to storage. The "product" will be placed in storage bins (not shown) ready for shipment. When secondary products are to be run, the vibrating screens will be changed to the required meshes.

In its preferred embodiment, the helical tube is molded of concrete.

All three embodiments of the invention have the same purpose, which is to change the geometrical shape of the rock particles from angular to spherical.

Throughout the description of the illustrated embodiments of the invention the means for impelling the rock particles through the tubes has been a fan creating winds of air of substantial force in the tubes. It is not necessary that the conveying medium be air. Other gases will work. It is only necessary that the conveying medium has a viscosity sufficiently low that it will not lubricate the impact between the moving and the stationary particles of rock and thereby prevent attrition of the particles in collision.

When collision occurs between impelled particles of rock and stationary particles of rocks as hereinbefore described the impact is of a very high order as compared with the impact between nearly parallel moving suspended particles, and such impact results in the fracture of the crystal structure of the rock particles. In effect it is a selective reduction of the more protruding parts of the grains of the rock particles with a consequent rounding of the particles being reduced in size. Applicant employs the invention to make a coarse sand and any powder size material obtained is a by product.

Depending on the nature of the rock particles being used, it may prove feasible to increase the wind range of the fans up to 500 miles per hour without pulverizing the particles. However, applicant contemplates using rock particles largely composed of quartz and has found that winds in excess of 200 miles per hour have caused the particles to pulverize each other rather than to fracture the grain structure of the particles.

I claim:

1. An impact mill for reducing the size of rock particles including an elongated tube of predetermined length having a receiving end and a discharge end, an attrition bin disposed in co-operative alignment with said tube and communicating with the discharge end thereof, means for introducing rock particles to said tube, means for impelling said particles through said tube at high velocity, whereby said particles are hurled from said discharge end into the attrition bin, said bin being adapted to accumulate at least some of said particles, said co-operative alignment of said bin with said tube serving to direct said particles hurled from the discharge end of said tube into collision with the particles accumulated in said bin to reduce the size of at least some of said particles.

2. An impact mill according to claim 1 in which the means for introducing rock particles to said tube includes a feed hopper detachably connected to the tube adjacent the receiving end thereof.

3. An impact mill according to claim 2 including an aperture for removing dust from said bin and a closable aperture in the floor of said bin through which rock particles can be withdrawn.

4. An impact mill according to claim 3 in which the means for impelling the particles at high velocity through the tube comprises a fan in the receiving end of said tube capable of creating high velocity winds in said tube in the range from to 50 to 500 miles per hour, said winds serving to force said particles to move at high velocity along said tube.

5. An impact mill according to claim 1 in which the tube is helical and the discharge end thereof is elevated relative to the receiving end thereof.

6. An impact mill according to claim 1 in which the tube is made of concrete.

7. An impact mill for reducing the size of rock particles, said mill including at least two elongated tubes of predetermined length and an equal number of attrition bins, each of said tubes having a receiving end and a discharge end; said bins being co-operatively aligned in

5 series with said tubes for the successive reduction of said particles; one of said discharge ends communicating with each of said bins; means for introducing rock particles to a selected first tube, means for impelling said particles through said selected first tube at high velocity into the bin communicating with the discharge end thereof, means for introducing rock particles in said bins to the receiving ends of said tubes, means for impelling said particles through said tubes at high velocity into the bins communicating with the discharge ends thereof, each of said bins being adapted to accumulate at least some of said particles, whereby said particles are impelled through said tubes from bin to bin and said co-operative alignment of said bins with said tubes serves to direct said particles impelled from the discharge ends of said tubes into collision with said accumulated particles in said bins to reduce the size of at least some of said particles.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
